US00D731513S

(12) **United States Design Patent**
Donahue et al.

(10) **Patent No.:** **US D731,513 S**
(45) **Date of Patent:** **** Jun. 9, 2015**

(54) **DISPLAY SCREEN WITH GRAPHICAL USER INTERFACE**

(71) Applicant: **Microsoft Corporation**, Redmond, WA (US)

(72) Inventors: **Megan Donahue**, Seattle, WA (US); **Chad Michael Roberts**, Snohomish, WA (US); **Josh Phillips**, Seattle, WA (US); **Rhoniel Villano Manlapaz**, Bellevue, WA (US); **Andrea Michelle Simons**, Shoreline, WA (US); **Nancy Yun Xu**, Seattle, WA (US)

(73) Assignee: **Microsoft Corporation**, Redmond, WA (US)

(**) Term: **14 Years**

(21) Appl. No.: **29/454,145**

(22) Filed: **May 7, 2013**

(57) **CLAIM**

The ornamental design for a display screen with graphical user interface, as shown and described.

DESCRIPTION

The FIGURE is a front view of a display screen with graphical user interface showing the new design.

The broken line showing of a device in the FIGURE illustrates environment and forms no part of the claimed design.
